(57) **CLAIM**

The ornamental design for the guard shield for a trimmer, as shown and described.

DESCRIPTION

FIG. 1 is a perspective view of a guard shield for a trimmer in accordance with the embodiment of the present invention; FIG. 2 is a front view of the guard shield for a trimmer of FIG. 1;

FIG. 3 is a rear view of the guard shield for a trimmer of FIG. 1;

FIG. 4 is a left side view of the guard shield for a trimmer of FIG. 1;

FIG. 5 is a right side view of the guard shield for a trimmer of FIG. 1;

FIG. 6 is a top side view of the guard shield for a trimmer of FIG. 1;

FIG. 7 is a bottom view of the guard shield for a trimmer of FIG. 1;

FIG. 8 is an enlarged front view of the guard shield for a trimmer taken from indication circle 8 in FIG. 2;

FIG. 9 is an enlarged rear view of the guard shield for a trimmer taken from indication circle 9 in FIG. 3; and,

FIG. 10 is an enlarged perspective view of the guard shield for a trimmer taken from indication circle 10 in FIG. 1.

The broken line showing of the trimmer in FIGS. 1-10 illustrate the environment of the claimed design and form no part thereof. The remaining broken lines in the drawings illustrate portions of the guard shield for a trimmer and form no part of the claimed design.

1 Claim, 7 Drawing Sheets
